ROTARY DRUM

Wilhelm Reintrock, Podusused, near Zagreb, Yugoslavia, assignor to the firm Fried. Krupp Grusonwerk Aktiengesellschaft, Magdeburg-Bückau, Germany

Application March 26, 1937, Serial No. 133,130
In Germany February 10, 1936

3 Claims. (Cl. 83—9)

My invention relates to rotary drums for grinding and similar operations, more particularly to such drums of uniform circumferential shape provided with longitudinal partition walls arranged in star fashion whereby the drum is divided into a number of chambers surrounding the axis of rotation.

The charging of the individual chambers and the discharge therefrom takes place in such drums through the transverse walls of the drum, that is to say, through the end walls of the drum or through inner walls lying parallel thereto. With this arrangement it often occurs that the charging and discharging do not take place uniformly, and consequently the individual chambers receive charges of varying amounts. Apart from the fact that the most favorable utilization of the arrangement is not realized, the power required for the rotation of the drum is also increased, because the drum is unevenly loaded by the varying charge and in this way a fluctuating driving force is required.

According to my invention the length of the longitudinal partition walls is made smaller than the distance between the transverse walls enclosing them, so that they terminate at a distance from the said transverse walls at one or both ends. In this way, a free zone is formed in the drum between the end of the longitudinal partitions and the transverse wall. Since the drum is of uniform diameter, there is no step between this free zone and the chambers. Thus, the contents of the individual chambers fall or roll during rotation of the drum partly into this free zone and back into the chambers, whereby a constant compensation automatically progresses between the individual chambers in respect of their filling.

In order to prevent too great a falling or flow of the contents from the chambers, I provide the longitudinal partition walls at their free end with a flange which may extend to the wall of the drum, or I let them abut against a plate which leaves a passage free between the edges of the partition walls and the wall of the drum. The partition walls may also be curved in spiral fashion, preferably near to their free ends, instead of lying parallel to the axis. This curvature may extend in the direction of rotation of the drum or inversely with respect thereto. It thus conveys the contents of the chambers, in the first case on the charging side and in the second case on the discharging side, more forcefully into the free zone than would a wall of parallel axis, so that the compensation is increased, while in

both the other cases it has an impeding action and thus brings about a sifting during falling out.

In order that my invention may be clearly understood and readily carried into effect the same will now be more fully described with reference to the accompanying drawing illustrating a constructional example of the invention.

Figure 1 represents a grinding drum in longitudinal section.

Figures 2 and 3 represent cross sections on the lines II—II and III—III of Figure 1 respectively.

The improved machine is mounted on a suitably-constructed frame 10, in which is journaled a rotary drum consisting of the peripheral wall 11 and the two end walls 12 and 13 the former carrying the trunnion 14. A suitable driving device 15 is provided for imparting a rotary motion to the said drum. By the feeding spout 16 the material to be handled is charged to the drum 17 through the passage of the trunnion 14. At the discharging end of the drum the stationary outlet 17 is provided embracing the end wall 13. The interior space of the drum is divided into zones A and B by the transverse walls 18, 19 and 20, these walls being provided with passages in the form of slots.

In the said zones, longitudinal partitions are arranged, the partitions 21 between the transverse walls 18 and 19 terminating at each end at a distance from the latter, so that between them and the transverse walls at each end a free zone R traversing the entire cross section of the drum is formed. The longitudinal partitions 21 are, as is shown in Figure 2, arranged in star fashion to subdivide the inner space into grinding chambers K. At their edges facing towards the transverse wall 18, they are provided with flanges 22 on that side on which the contents of the drum are situated during upward rotation in the direction of the arrow x in Figure 2, the outer ends 22' of the said flanges extending to the peripheral wall 11 of the drum, while their inner ends 22'' form a disc about the axis.

At the other end, that is, on the side facing towards the transverse wall 19, the partition walls 21 terminate in a spirally curved part 21', which is curved in the direction of rotation of the drum, as is shown in Figure 2.

The material which has passed through the transverse wall 18 is uniformly distributed from the free zone in front of the longitudinal partitions 21 into the individual chambers formed by the said partitions 21. The flanges 22 prevent material required for the proper filling from re-

turning, but allow any surplus which may have passed into any of the chambers to fall back into the initial free zone.

The spiral formation 21' of the partitions 21 5 at the outlet end favours the passing out of the ground material.

The longitudinal walls 23, which are arranged in zone B between the transverse partitions 19 and 28, as is shown in Figure 3, are not inserted 10 radially, but each partition forms an angle with the radial direction whereby a solid part 24 about the axis of the drum is formed, which remains unused. As this zone serves for the finer grinding, the longitudinal partitions here lie level and 15 parallel to the axis of the drum. They extend to the closing transverse wall 20, through which the completely ground material passes out.

My invention affords the further advantage 20 that the individual chambers are accessible from the free zone, and may therefore be cleaned, and when necessary charged with new grinding bodies from this zone. It is therefore no longer necessary to provide a man-hole in the jacket of the 25 drum for each individual chamber, whereby the drum is cheapened and strengthened.

Having now particularly described and ascertained the nature of my said invention, and in what manner the same is to be performed, I declare that what I claim is:

30 1. In a device of the kind described, a peripheral wall forming a drum of uniform cross-section, means supporting said drum for rotation, means for rotating said drum, perforated transverse walls in said drum, and longitudinal partitions 35 between said transverse walls extending from the axial midsection of the drum to the peripheral wall thereof and terminating in a closed central hub to subdivide the inner space of the drum into grinding chambers, the axial 40 length of said partitions being sufficient to cause a repeated tumbling of the material in its travel along them, but less than the distance between the transverse walls enclosing them, so that at least at one end of said partitions there is a free 45 zone between the ends of the partitions and the adjacent transverse wall which communicates openly with said grinding chambers.

2. In a device of the kind described, a peripheral wall forming a drum of uniform cross-section, means supporting said drum for rotation, means for rotating said drum, perforated transverse walls in said drum, and longitudinal partitions 5 between said transverse walls extending from the axial midsection of the drum to the peripheral wall thereof and terminating in a closed central hub to subdivide the inner space of the drum into grinding chambers, the axial length of said 10 partitions being sufficient to cause a repeated tumbling of the material in its travel along them, but less than the distance between the transverse walls enclosing them, so that at least at one end of said partitions there is a free 15 zone between the ends of the partitions and the adjacent transverse wall which communicates openly with said grinding chambers, the space between each adjacent pair of partitions being wholly open to said free zone, with the exception 20 of a flange on each partition extending slightly above the side of the partition which faces upward when the partition is moving upward, to hold the material to be ground to a certain depth 25 on the partition.

3. In a device of the kind described, a peripheral wall forming a drum of uniform cross-section, means supporting said drum for rotation, means for rotating said drum, perforated transverse walls in said drum, and longitudinal partitions 30 between said transverse walls extending from the axial midsection of the drum to the peripheral wall thereof and terminating in a closed central hub to subdivide the inner space of the drum into grinding chambers, the axial 35 length of said partitions being sufficient to cause a repeated tumbling of the material in its travel along them, but less than the distance between the transverse walls enclosing them, so that at least at one end of said partitions there is a free 40 zone between the ends of the partitions and the adjacent transverse wall which communicates openly with said grinding chambers, said partitions being substantially plane for the most part, but spirally curved at their effluent ends. 45

WILHELM REINTROCK.
